NONRAVELING KNITTED FABRIC

Karl Maier, Meaux, France

Application April 12, 1937, Serial No. 136,411
In France April 11, 1936

5 Claims. (Cl. 66—169)

(Granted under the provisions of sec. 14, act of
March 2, 1927; 357 O. G. 5)

The present invention relates to nonraveling hosiery and the manufacture thereof, and it is more especially applicable to articles made on a flat frame and more especially on a Cotton frame.

Various systems of interlocking the loops have already been suggested for ensuring a special connection between them and thus obtaining a practically nonraveling article. But these suggestions involve serious drawbacks in that they permit of obtaining the desired result only to a limited degree because the articles knitted according to these methods no longer have the smooth aspect of ordinary knitted goods and lose the elasticity which characterizes knitted goods, or because the carrying out of these methods calls for a fitting of the frame with devices which are difficult to adapt to said rectilinear frames and in particular to the Cotton frame, whereby said methods cannot be used for practical purposes.

The knitted fabric according to the present invention is free from the first mentioned drawback in that it has a smooth appearance while keeping a satisfactory elasticity.

Furthermore, the manufacture of the knitted fabric requires but an easy modification of the frame. For instance the latter may be completed on the one hand by an auxiliary presser member, disposed parallelly to the usual pressure member, which is kept without any modification in its form or its operation, on the other hand by a series of small blades or swinging parts disposed opposite each needle, between the latter and the usual presser member, said swinging parts being carried by the frame of the knocking over bits. Furthermore, the knocking over bits are subjected to a slight modification in order to create behind the existing throat a notch or second throat. This particular arrangement of the frame, which can easily be provided has not the above mentioned drawback and it permits a practical construction and use.

Among other methods suggested for the obtainment of a nonraveling knitted fabric, it is known to make use of two yarns of different lengths, employed both in each course (that is to say in each horizontal line of loops). One of the yarns, the longer one, forms, on the outer face of the fabric, loops for all needles, and this in the usual manner. On the contrary, the second yarn, the shorter one, forms loops only on some needles, leaving a stretched portion from one loop to the other opposite the intermediate needles.

According to the present invention, the long 55 yarn which is included in each course of loops

is sunk and shaped in such manner as to constitute alternately, from one wale of loops to the other (the word wale designating the vertical lines of loops) a long loop extending over two successive courses of loops and a short loop formed on the first of the two above mentioned courses of loops. The short yarn is sunk in such manner as to constitute on the other hand a retaining loop for the long loop above mentioned and on the other hand in the next course a loop which is superposed to the short loop constituted by the long yarn. 5

In other words, the long yarn forms in each course, alternately, a long loop and a short loop, and the short yarn forms, alternately, a loop which is juxtaposed to the short loop constituted by the long yarn and an ordinary loop which retains the long loop formed by the long yarn. It follows that the knitted fabric made according to this method has a connection not only in the horizontal and vertical directions but also diagonally, which has for its effect to eliminate the injurious action of a longitudinal pull exerted parallelly to the wales of loops, whereas the action of a transverse pull, that is to say along a course of loops is remedied by the double length of the long loops extending over two courses of loops. It is therefore clear that the article knitted according to this process cannot ravel at all, an advantage which is particularly advantageous in the case of stockings or similar articles. 20 25 30

It is clear that this system involves various embodiments. This results from the fact that the long loop formed by the long yarn can extend over any number of courses of loops, for instance three successive courses. Furthermore, it is possible to insert between the alternate courses of long and short loops (the long loops extending over two successive courses), a course of smooth 40 short loops in which all the needles form short loops with a short yarn. In such an arrangement, I obtain a pattern similar to that of the Jacquard, the double loops (two juxtaposed loops), which project with respect to the simple 45 smooth loops, forming patterns. Of course, instead of a single course of smooth loops, I may interpose a great number of courses of said loops, in such manner that other patterns appear on the right side of the knitted fabric. 50

Other features of the present invention will result from the following detailed description of some specific embodiments thereof.

Preferred embodiments of the present invention will be hereinafter described, with reference 55

- to the accompanying drawings, given merely by way of example, and in which:
- Fig. 1 shows the back side of an ordinary knitted fabric;
- 5 Fig. 2 shows the back side of a knitted fabric manufactured according to the present invention;
- 10 Figs. 3 and 4 show, on the back side, modifications of knitted fabrics made according to the present invention;
- 15 Fig. 5 is a transverse section, on an enlarged scale, opposite a needle, showing the arrangement of the different members necessary for carrying out the present invention;
- 20 Fig. 6 and 7 are views, analogous to Fig. 5, some parts being in a different position;
- 25 Fig. 8 is a plan view of the auxiliary presser member;
- 30 Fig. 9 is a detail view of a knocking over bit modified according to the invention;
- 35 Fig. 10 is a perspective diagrammatical view showing how the elements shown by Fig. 5 are controlled;
- 40 Figs. 11 to 24 are diagrammatical views illustrating the different steps of the manufacture of the knitted fabric according to the present invention.
- 45 Adverting to Fig. 5, the drawings show the elements of a flat frame of the "Cotton type," to wit: the needle 1, looping sinker 2, knocking over bit 3, presser member 4.
- 50 According to the present invention, the frame is completed by a second presser member, or auxiliary presser 5, and by a series of small blades or swinging parts 6. Each of these blades is located opposite a needle and can pivot about axis 7 in the direction of arrow F under the action of the presser member 5 and against the action of spring 8. The axis 7 is carried by the frame 7a of the knocking over bits.
- 55 The drive of the presser member 5 is obtained in the following manner:
- 60 Arms 9 (Figs. 5 and 10) connect presser member 5 to levers 10 keyed on a shaft 11. This shaft 11 is subjected to the action of a cam 12 through the medium of the lever 13, pivoted at 14. This lever 13 is articulated at 15 to a link 16 which is pivotally connected at 18 to a lever 17 keyed on shaft 11, so that said shaft 11 is given a reciprocating oscillatory motion which produces the forward and rearward movement of the presser member 5, which thus acts on blades 6 for tipping them in the direction of arrow F.
- 65 Shaft 11 is further subjected to a translatory movement in the direction of its axis, said movement being produced by the action of a wedge cam 19 acting upon roller 20. This cam 19 is displaced vertically by the action of the cam 21, fixed at 180° with respect to cam 12 on the same shaft 22. The movement is transmitted through arm 23, pivoted at 24, connected through its end 25 with the link and lever structure 26—27, articulated at 28, lever 27 being keyed on shaft 29 and driving cam 30 in connection with roller 31
- 70 the support of which is connected through a link transmission 32—33 with the cam 19 capable of sliding in slideway 34. A spring 35 ensures the return of shaft 11 and keeps roller 20 in contact with cam 19.
- 75 Of course, the connection between shaft 11 and lever 17 is such as to permit the free sliding in the longitudinal direction of said shaft 11.
- A disc 36, on which roller 37 runs normally, is juxtaposed to cam 21 and a suitable control 75 permits of displacing lever 23 laterally for bringing roller 37 into a position in which it runs on cam 36, in order to bring into action cam 30 and thus to produce the translatory motion of shaft 11.
- The control of roller 37 can be carried out as follows:
- 80 A lever 38 is pivoted at 39 and is connected to a shaft 40 at one of the ends of which there is pivotally mounted a bell crank lever 41, pivoted at 42. The arm 43 of this lever can be lifted by a boss 44 carried by an endless chain 45 which is given a suitable translatory movement.
- 85 As it will be readily understood, boss 45, when meeting arm 43, causes lever 38 to pivot against the action of return spring 46, in such manner that roller 37 is brought into coaction with cam 15 21 (Fig. 10).
- 90 The auxiliary presser member 5 (Fig. 10) has its front edge (on the side carrying swinging members 6) provided with teeth as it is visible on the plan view of Fig. 8. The pitch of these teeth is such that opposite the respective swinging members 6, there is alternately a tooth 48 and a hollow 49.
- 95 Swinging members 6 each terminated, as shown by Fig. 5, by a nose 50 arranged opposite the usual presser member 4. It is through these noses 50 that the needles are pressed, that is to say that the ends of their beards are driven into their eyes.
- 100 According to the invention, and in addition to the new members above described, the knocking over bits 3 (Fig. 9) are of particular shape in that they are completed by a throat 51, provided behind the ordinary throat 52 and in line with rib 53.
- 105 I have now described the structure of the frame capable of carrying out knitting according to the present invention. The following explanations will permit of understanding how said knitted article is made.
- 110 Adverting to Fig. 1, it is seen that in an ordinary knitted fabric the needle loops a are connected to one another merely by the sinker loops b, and this as well from one wale to the next one as from one course to the next one. 45 If, in such a knitted fabric, a yarn is broken, for instance at x (as a result of a hole in a stocking or similar article), the lateral pull exerted in directions c, d (parallel to the courses of loops) and the longitudinal pull in directions e, f (parallel to the vertical wales of loops), these pulls being generally produced merely by the natural play of the muscles of the leg when walking, it is noted that the stocking ravel upwardly and downwardly, in directions f and e.
- 115 In order to prevent raveling of a knitted article it is therefore necessary to eliminate or to render harmless both the action of the longitudinal pull (direction ef) and the action of the transverse pull (direction cd). According to the invention, 60 this double result is obtained in the following manner, as shown by Fig. 2:
- 120 Considering yarn g, it is seen that, in the course, this yarn is shaped in such manner as to constitute at h a small loop, in the next wale a long loop i and again a small loop h and so on, that is to say alternately a small and a long loop.
- 125 This alternative provision of small and long loops exists not only in the direction of the 70 courses but also in the direction of the wales. For instance, it will be noted that yarn g¹ is shaped in such manner as to constitute a long loop i¹ in line with the small loop h and a small loop h¹ in line with the long loop i.

The small loops h or h^1 are formed by two yarns, to wit yarn g or g^1 and the yarn m or m^1 , which further acts as retaining loop o or o^1 for the long loops i and i^1 . Thus it is seen that the 5 sinker loops k extend diagonally between each double loop, that is to say connect loops h to loops h^1 . This arrangement of the sinker loops k has for its result to eliminate the action of the longitudinal traction or pull (direction ef) and 10 the presence of long loops i has for its purpose to eliminate the detrimental action of the transverse pull or traction (direction cd).

As a matter of fact, when a hole is made which 15 causes a yarn to break, the long needle loop i cannot slide through the short retaining loop o , which is located below it because yarn m , which constitutes this retaining loop o , undergoes at the same time a stretching due to the lateral elongation in direction cd and because no other 20 expansion of long yarn g which constitutes the long loops i is possible, whereby a portion of long loop i , which is not subjected to a pull remains suspended in the short loop o , which has just undergone a stretching.

25 I have thus eliminated the detrimental action of the longitudinal pull or traction in direction ef on long loop i , which has now become free upwardly (direction f) due to the breaking of the loop in the preceding course, because the 30 short yarn m , of which the short retaining loop o is made, said loop o being located below the long loop i that has become free, forms with the long yarn g , of which the long loop i is made, the short double loop h disposed directly adjacent as 35 well the long loop i as the short loop o disposed below the latter, the yarn m being consequently disposed diagonally. This diagonal connection causes the whole of the longitudinal pull or traction to act upon the short retaining loop o which 40 has still a full connection and the short yarn m of which undergoes in fact no other longitudinal pull or traction in direction ef , whereas the free long loop i is wholly discharged as a result of the excess of yarn it has with respect to loop o located under it and therefore remains suspended in loop o as if by a knot.

Fig. 2 also shows that, despite the arrangement of yarns m and g , of different lengths, there can never be produced an excess of yarn 50 projecting from the knitted fabric, and as well the long yarn g as the short yarn m are utilized for forming loops in all the wales in such manner that there exists in the knitted fabric no loose yarn.

55 Diagrams 11 to 24 illustrate how the above knitted fabric described with reference to Fig. 2, can be produced on the Cotton frame.

On these diagrams I have shown two series of figures on the one hand Figures 11 to 17, on the other hand Figures 18 to 24; the first series of figures shows the different steps of the manufacture of a wale of loops, for instance wale p (Fig. 2); the other series of figures shows, in correspondence with the first series, the same different steps for a wale of loops adjacent to the preceding one, that is to say for wale q .

Figs. 11 and 18 show the needle l of wale p and the needle l^a of wale q , supplied with the yarn m^1 which has just been distributed and has 70 been shaped by sinkers 2. One sees on the knocking over bits 3 the loops of the preceding course that is to say (Fig. 11) the double loop h and (Fig. 18) the long loop i .

The needles fitted with the yarn m^1 thus move down as shown by Figs. 12 and 19.

In an ordinary frame, in the course of this downward movement, the needles are all pressed, that is to say the beards of said needles, when meeting with the front edge of the presser member, are driven into the eyes of said needles, but it has been explained above that the frame is fitted with an auxiliary presser member 5 acting upon swinging members 6 and it was also explained that this presser member 5 is toothed and consequently acts upon every second swinging 10 member.

It follows that, during the downward movement of the needles, only needle l will be pressed, as shown by Fig. 12, whereas needle l^a will move downwardly without being pressed (Fig. 19). 15 Needle l is pressed as a consequence of the fact that presser member 5 (Fig. 5) has been given a forward movement in the direction of arrow F , this movement being produced by the action of the cam 12, Fig. 10.

The general view of Fig. 5 shows the elements of the frame when needle l is pressed by the action of the auxiliary presser member 5.

In the course of this downward movement, the 25 yarn g , which constitutes the long loop i , penetrates under the beard of needle l^a and comes adjacent the yarn m^1 , precedingly hooked (Fig. 20).

On the contrary, as shown by Fig. 13, the double loop h has been normally knocked over on the 30 yarn m^1 and this in the supplementary throat 51, created for this purpose in the knocking over bits 3. Yarn m^1 thus forms the loop o^1 which will act as retaining loop for the long loop i^1 in 35 the next course.

Needles l and l^a move back upwardly and come to hook the yarn g^1 , serving to constitute the next course. This yarn g^1 is distributed of a 40 length greater than the length of yarn m^1 precedingly distributed.

Figs. 14 and 21 show the yarn g^1 caught respectively by needles l and l^a after said yarn has been sunk by sinkers 2. It will be noted (Fig. 21) that yarn m^1 at the place of needle l^a is carried by the nib 53 of the bit 3, whereas the 45 sinker loop of the needle loop i is engaged in the usual throat 52.

In Fig. 14, it is seen that loop o is placed under the throat 52 of bit 3, this in the usual manner. The yarn m^1 (Fig. 21) has remained on the nib 50 50 as a consequence of the fact that no knocking over of the loop has taken place; it is maintained in this position by needle l^a .

Yarn g^1 being locked in by needles l and l^a , the latter move downwardly.

In the course of this movement, all the needles are pressed by the action of the ordinary presser member 4, which acts as shown by Fig. 7 on the nose 50 of each swinging part 6 (the comparison between Fig. 6, which shows the knocking over 60 bit frame l^a in the position of rest, and Fig. 7, which shows this frame at the time of the action of the presser member 4, clearly shows how this action of pressing the needles takes place through the medium of the swinging members 6). 65

Figs. 15 and 22 show the needles l and l^a when they have been pressed by the action of the presser 4. It should be noted that this pressing action takes place only when the end or point of the beard of the needle has come a little below the upper ridge of nib 53, in such manner that, when the beard is pressed, the yarn m^1 (held by said upper ridge) has been caught in the beard; it is therefore locked in in the same manner as yarn g^1 as shown by Fig. 22.

The needles further move downwardly and the preceding loop of every wale is knocked over, these preceding loops being loop o^1 for yarn g^1 (Fig. 16) and loop i for yarn g .

5. In the course of the knocking over movement, it is known that bits 3 are displaced with a translatory movement in the direction of arrow F^1 (Figs. 17 and 24).

In the course of this translatory movement of 10 the bits, the throats 52 of said bits push in the direction of the arrow F^1 the course of loops pre- cedingly established, that is to say the short loops o^1 (Figs. 16 and 17) and the long loop i (Figs. 23 and 24).

15. As it will be readily understood, this translatory displacement of the bits 3 differently bends needles 1 and 1a. As a matter of fact, needle 1, which has locked in only the yarn g^1 distributed in a loose manner, pulls on this yarn and forms 20 a long loop i^1 (Fig. 17), while needle 1a, which has locked in at the same time the yarn g^1 distributed long and yarn m^1 distributed short, is driven by the latter and as a consequence of this traction and due to its flexibility said needle is brought 25 into the position shown by Fig. 24.

The excess of long yarn g^1 , distributed opposite needle 1a, is therefore absorbed and permits consequently the formation of the long loop i^1 on needle 1.

30. As a result of the translatory displacement of the knock over bits, the yarn g^1 is therefore suitably distributed and stretched on the needles 1 and 1a, as shown by Fig. 2, and the loop of yarn g^1 , which constitutes the double loop h^1 , is of 35 the same length as the loop of yarn m^1 , which also constitutes the double loop h^1 . In the next row, the cycle is repeated but the needles 1a will work in the manner above described with 40 reference to needles 1 and the latter will work in the manner above described with reference to needles 1a.

This change of function of the needles is determined by the action of the presser member 5 which is displaced in the direction of its longitudinal axis, as above explained, by the action 45 of the cam 21 and of cam 19. The length of this displacement is of course equal to the width of the teeth 48 of presser member, in such manner that teeth instead of being located opposite needles 1 are now located opposite needles 1a.

Fig. 3 shows, seen on the back side, a nonraveling knitted fabric which can be obtained according to the present invention.

As shown by this figure, it is possible to choose 55 the arrangement of the yarns in such manner that the needle 1 of the wale p , after having formed the double short loop h , as shown by Fig. 2, that is to say with yarns m and g , forms a loop l with yarn n distributed a little longer than yarn m , 60 but shorter than yarn g , whereas needle 1a of course q is not pressed and thus forms a loop which will be knocked over at the same time as the long loop i of the wale q on the double loop h^1 constituted by yarns m^1 and g^1 . With 65 this arrangement, the long loops i are, as clearly shown, longer than the loops i preceedingly obtained as shown by Fig. 2.

Fig. 4 relates to another embodiment of nonraveling knitted fabric in which there is inter- 70 posed between the long loop i^1 and the double short loop h (Fig. 2) a smooth course of simple loops.

This knitted fabric is obtained in the following manner: After having made loop h on the 75 needle 1 of wale p , I distribute a short yarn r

with which are formed short loops, as shown at s , and this for each wale p and q .

Then I distribute the yarn m^1 , as shown by Fig. 2, and a new long yarn g^1 , and so on.

In such an arrangement, I obtain a pattern 5 similar to a Jacquard pattern as a consequence of the fact that the double loops h project, with respect to the smooth loops s and o and thus form patterns. Of course, it is possible to introduce at will a great number of courses of simple 10 loops by distributing yarns r over as many courses as it is desired, in such manner that other patterns always appear on the right side of the knitted fabric.

It will be readily understood that it is possible 15 to make knitted fabrics according to any desired arrangement and in particular according to those illustrated by Figs. 3 and 4, with the elements above described, with reference to Fig. 5 and Fig. 10. As a matter of fact, the looping is a function 20 partly of the movement of the auxiliary presser member 5 and this movement can be modified at will through the action of cams 12 and 21, which can be brought into play at the proper time.

In a general manner, while I have, in the above 25 description, disclosed what I deem to be practical and efficient embodiments of the present invention, it should be well understood that I do not wish to be limited thereto as there might be changes made in the arrangement, disposition 30 and form of the parts without departing from the principle of the present invention as comprehended within the scope of the appended claims.

In these claims, it should be well understood 35 that the word "courses" applies to the geometrical courses as they appear on the drawings.

What I claim is:

1. A nonraveling knitted fabric including a plurality of successive horizontal courses of loops 40 forming vertical wales, in which fabric at least some courses include, at least in some of their loops, two yarns, a long yarn and a short yarn, the long yarn forming in each of said last mentioned courses, alternately from one wale to the 45 next one, a short loop corresponding to the height of one course and a long loop corresponding to the height of at least two courses, and the loops of long yarns in each vertical wale being alternately a long loop and a short loop, in such manner that the long loops are arranged in staggered relationship, the short yarn forming alternately in one wale a short loop superposed to a short loop of the long yarn, then, in the next wale and the preceding course, a short loop interposed, in 55 the vertical direction, between a short loop and a long loop of long yarns, these second mentioned short loops of short yarn being adapted to retain and fix the long loops of long yarn, whereby raveling is prevented. 60

2. A nonraveling knitted fabric including a plurality of successive horizontal courses of loops forming vertical wales, in which fabric at least some courses include, at least in some of their loops, two yarns, a long yarn and a short yarn, 65 forming alternately, in the courses, a simple long loop and a double short loop, the long yarn forming in each of said last mentioned courses, alternately from one wale to the next one, a short loop corresponding to the height of one course 70 and a long loop corresponding to the height of at least two courses, the loops of long yarns in each vertical wale being alternately a long loop and a short loop, in such manner that the long loops are arranged in staggered relationship, the 75

short yarn forming alternately in one wale a short loop superposed to a short loop of the long yarn, then, in the next wale and the preceding course, a short loop interposed, in the vertical direction, 5 between a short loop and a long loop of long yarns, these second mentioned short loops of short yarn being adapted to retain and fix the long loops of long yarn, whereby raveling is prevented.

3. A nonraveling knitted fabric including a plurality of successive horizontal courses of loops forming vertical wales, in which fabric every second course includes two yarns, a long yarn and a short yarn, the long yarn forming, in the direction of said courses, alternately from each 10 wale to the next one, a short loop corresponding to the height of one course and a long loop corresponding to the height of two courses, the loops of long yarn in each vertical wale being alternately a long loop and a short loop, in such manner that the long loops are arranged in staggered 15 relationship, the short yarn forming, alternately, in one wale a short loop superposed to a short loop of the long yarn, then, in the next wale and the preceding course, a short loop interposed, in the vertical direction, between a short loop and a long loop of long yarn, these second mentioned short loops of short 20 yarn being adapted to retain and fix the long loops of long yarn, whereby raveling is prevented, the successive loops in each vertical wale being, a short double loop of long 25 yarn and short yarn, a short single loop of short yarn, and a long single loop of long yarn, and so on.

4. A nonraveling knitted fabric including a plurality of successive horizontal courses of loops forming vertical wales, in which some courses include two yarns, a long yarn and a short 30 yarn, the long yarn forming, in the direction of said courses, alternately from each wale to the next one, a short loop corresponding to the height of one course and a long loop corresponding to the height of three courses, the loops of long 35 yarn in each vertical wale being alternately a long loop and a short loop, in such manner that the long loops are arranged in staggered relationship, the short yarn forming, alternately, in one wale a short loop superposed to a short loop of long 40 yarn, then, in the next wale and the preceding course, a short loop interposed, in the vertical direction, between a short loop and a long loop of long 45 yarn, these second mentioned short loops of short yarn being adapted to retain and fix the long loops of long yarn, whereby raveling is prevented, and a third yarn forming alternately, in the direction of the courses, in one wale a short loop interposed, in the vertical direction, between a long loop of long yarn and a short loop of long 50 yarn, and, in the next wale and the preceding course, a short loop interposed, in the vertical direction, between a double short loop of short and long yarns and a short loop of short yarn, the successive loops in each vertical wale being a short double loop of long and short yarns, a short loop of short yarn, a long loop of long yarn, a short loop of third yarn, and so on.

loop of long yarn, these second mentioned short loops of short yarn being adapted to retain and fix in position the long loops of long yarn whereby raveling is prevented, other courses interposed between the above mentioned courses, consisting of a third yarn longer than the above mentioned short one and shorter than the above mentioned long one, forming, alternately, a short loop which interlocks a double loop of the adjacent row with a short retaining loop of short yarn, and a long 10 loop superposed to the end of the corresponding long loop of long yarn, the successive loops in each vertical wale being, a short double loop of long and short yarns, a short loop of third yarn, a short loop of short yarn, and a long loop of long 15 yarn, and so on.

5. A nonraveling knitted fabric including a plurality of successive horizontal courses of loops forming vertical wales, in which fabric some courses include two yarns, a long yarn and a short 20 yarn, the long yarn forming, in the direction of said courses, alternately from each wale to the next one a short loop corresponding to the height of two courses, the loops of long yarns in each vertical wale being alternately a long loop 25 and a short loop, in such manner that the long loops are arranged in staggered relationship, the short yarn forming alternately, in one wale, a short loop superposed to a short loop of long yarn, then, in the next wale and the preceding course, 30 a short loop interposed, in the vertical direction, between a short loop and a long loop of long yarn, these second mentioned short loops of short 35 yarn being adapted to retain and fix the long loops of long yarn, whereby raveling is prevented, and a third yarn forming alternately, in the direction of the courses, in one wale a short loop interposed, in the vertical direction, between a long loop of long 40 yarn and a short loop of long yarn, and, in the next wale and the preceding course, a short loop interposed, in the vertical direction, between a double short loop of short and long yarns and a short loop of short yarn, the successive loops in each vertical wale being a short double loop of long and short yarns, a short loop of short 45 yarn, a long loop of long yarn, a short loop of third yarn, and so on.
